UNITED STATES PATENT OFFICE

WILLIAM WALLACE KEMP, OF BALTIMORE, MARYLAND, ASSIGNOR TO THE C. M. KEMP MFG. CO., OF BALTIMORE, MARYLAND, A CORPORATION OF MARYLAND

MUFFLE FURNACE AND METHOD OF OPERATING THE SAME

Application filed August 29, 1927. Serial No. 216,313.

The present invention relates to improvements in muffle furnaces and method of operating the same. One of the primary objects of the invention is to provide for excluding from the interior of the muffle of such a furnace, gases generated in the furnace and further to utilize some of the waste heat of the combustion gases for heating the interior of the muffle.

10 As the invention is particularly applicable for use with continuously fired furnaces for enameling cast iron or steel bodies in which the muffle is heated by gas, such an embodiment is illustrated in the accompanying drawings, but the invention is not to be understood as being thereby, in its broader aspects, limited to a furnace for this particular character of work or of the gas heated type.

In furnaces of the type referred to, the 20 muffles are commonly made of refractories and it is a matter of considerable difficulty, and expense, to prevent the introduction into the muffle, through the more or less porous walls, of gases from the combustion chamber of the furnace.

In porcelain enameling furnaces such gases, particularly the carbon dioxide content thereof, have a deleterious effect on the enamel causing a pitting or roughing of the 30 enameled surface and preventing obtaining the desired smoothness.

To avoid this objection, it has been proposed to cause such a "stack pull" or draft through the combustion chamber of the furnace as to actually produce a slight vacuum in that chamber. This has operated to draw cold air from the surrounding atmosphere into the muffle, the back wall of which is frequently the back wall of the furnace, or 40 through the slight space or crevice which is generally present about the edges of the muffle door.

The result of this operation, is that the amount of fuel which must be consumed in 45 order to maintain the interior of the muffle

at the desired temperature is relatively large; and there is a very considerable waste of high temperature gases through the furnace stack. Again, the cold air which is drawn into the muffle, as above referred to, is heated there- 50 in and drawn outward through the walls thereof into the combustion chamber or furnace. The heat which is acquired by this air is that which has been produced by radiation from the inside of the muffle walls, and is, 55 therefore, relatively expensive.

By the present invention, means are provided whereby a furnace of the type referred to may be operated with a relatively small amount of fuel, and in which a maximum 60 amount of the heat generated in the combustion chamber will be utilized so that the operation of the improved furnace will be relatively considerably less expensive than that incident to operating furnaces of the 65 same general type, as commonly constructed.

The invention will now be described more in detail in connection with the accompanying drawings, in which:

Figure 1 is a longitudinal vertical section 70 and partial side elevation of a gas fired enameling furnace embodying the present invention.

Figure 2 is a transverse vertical section substantially on the line 2-2 of Figure 1. 75

Figure 3 is a plan view.

Figure 4 is a section substantially on the line 4-4 of Figure 2.

In the drawings, it will be understood that the parts are shown more or less conventionally and diagrammatically, and there can, of course, be considerable variation from some of the details illustrated without departing from the invention.

Referring to the drawings, in the several views of which corresponding parts are designated by the same references characters 1 designates the combustion chamber of a gas fired enameling furnace which, as shown, is provided with suitable bottom, side and top 90

walls, the side and top walls being enclosed by an outer wall or casing 2.

Within the combustion chamber 1 is supported a suitable refractories muffle 3. As shown, the bottom of the muffle rests upon piers or columns 4 spaced longitudinally of the combustion chamber so as not to interfere materially with the flow of gases from the burners 5 which are positioned in alignment with suitable apertures or openings 6 formed in the side walls of the combustion chamber in a plane below the bottom of the muffle 3.

As is customary, the burner openings 6 are arranged out of alignment and such openings are preferably of the form shown in Figure 2, that portion thereof within the furnace casing 2 flaring outward slightly for a purpose to be hereinafter referred to.

It will be seen that the furnace combustion chamber 1 extends completely around the muffle, the top and side walls of the latter being relatively closer to the adjacent walls of the furnace than the distance separating the bottom of the muffle from the bottom of the combustion chamber.

The combustion chamber communicates through passages 7 formed in the arched top of the inner furnace wall with a flue 8, that extends longitudinally of the furnace and communicates at one end with the stack 9 through which the waste products of combustion from the furnace escape.

The burners 5 are arranged in two groups at opposite sides of the furnace, the members of each group being connected to a suitable manifold 10 which, in turn, is connected to a branch main or supply pipe 11.

The joint 12 between each manifold 10 and its supply pipe 11 is of such nature that the burners may be swung outward away from the furnace wall as a unit (turning about the axis of the manifold 10) when the furnace is shut down as represented in dotted lines in Figure 2. This arrangement permits the burners to be positioned relatively remote from the walls of the furnace when not in use so that they are not subjected to the radiated heat from the furnace chamber and the life of the burners is thereby lengthened.

According to the present invention, means are provided for preventing the gases of the products of combustion entering the muffle 3 and affecting the articles being treated therein. Such means in the embodiment of the invention illustrated, comprise a blower 20 which, through a pipe 21, is connected with a recuperator 22 located in the furnace stack 9. The recuperator connects the pipe 21 with a conduit or pipe 23 that extends longitudinally of the furnace duct 8, and is provided with depending outlet branches 24 that extend through the ducts 7 and the top of the muffle 3 into the interior of the latter.

According to the invention, the blower 20

is operated to force air through the conduits 21, 23 and the interposed recuperator, so that the same is delivered into the muffle 3 at a pressure not less than that produced by the combustion in the furnace combustion chamber. This air, it will be noted, is pre-heated in passing through the recuperator 22, the stack 9 and the duct 8 so that it enters the muffle at a sufficient temperature to prevent withdrawing any particular amount of heat from the walls of the muffle.

As above stated, the air is supplied to the muffle under a pressure sufficient to overcome the pressure in the combustion chamber, and will thus prevent combustion gases from entering the muffle. According to the present invention, the combustion gases will be maintained in the furnace under slight pressure, instead of under a partial vacuum as has been the common practice heretofore with furnaces of the same type. This pressure within the furnace can be maintained and regulated by a damper 25 located in the stack 9.

The blower 20 is represented as being located on top of the furnace in the drawings, but it will be understood that this is not a feature of the invention and is merely shown in order that the illustration of the entire apparatus may be complete. The blower may be of any suitable type and supported in any desired relation to the furnace. Preferably it would probably be located some distance from the furnace. The capacity of the blower is designed to be such that it will always supply an amount of air in excess of that which is required to be admitted to the muffle.

A suitable blow-off valve 21^a is provided in the pipe 21, and between this valve and the recuperator 22 is arranged an "index cock" 21^b, by means of which, the volume of air passing through the recuperator may be varied and regulated as desired.

In manipulating the furnace, it will probably be preferable to provide two pressure gauges, indicating respectively the pressures in the furnace chamber about the muffle and the pressure within the latter. By observing these two gauges, an operator can properly manipulate the index cock 21^b so that the pressure within the muffle will not be less than that in the combustion chamber.

While the embodiment of the invention illustrated is described as including gas burners, it will be appreciated that it is not limited to furnaces in which this particular heating medium is employed. Oil or other combustibles may be substituted if desired, and the apparatus and method described will effectually prevent gases from the combustion chamber gaining access to the interior of the muffle either through the more or less porous walls thereof, or through cracks or crevices that may exist between the walls, door, etc., of the muffle.

Access to the interior of the muffle 3 is had through an opening in the front wall of the furnace controlled by a suitable door 26. This, in the embodiment of the invention illustrated, is designed to be a sliding door, the inner face thereof and the corresponding wall being inclined slightly downward toward the bottom of the furnace. Such door may be of any suitable character.

10 It is believed that the operation of the improvements and advantages thereof will be readily appreciated from the foregoing description.

15 By supplying air pressure to the interior of the muffle 3, it is possible to effectually prevent any of the gases from the furnace combustion chamber 1 entering the muffle, and as such air is preheated the muffle walls are not chilled and reduced in temperature as has 20 been the case in furnaces of the same type as commonly constructed. By the invention, it is possible to maintain the gases in the combustion chamber of the furnace under slight pressure instead of a vacuum and thereby effect 25 a material reduction in the amount of gas required to properly heat the muffle.

What I claim is:—

1. The herein described method of operating muffle furnaces including a combustion chamber and a refractories muffle comprising maintaining pressure in both the combustion chamber and muffle, the pressure within the muffle being such as to prevent the admission thereto of gases from the combustion chamber, for the purpose described.

2. The herein described method of operating muffle furnaces including a combustion chamber and a refractories muffle, comprising heating the muffle by passing through 40 the combustion chamber heated gases under pressure, and maintaining within the muffle a pressure not less than that of the gases in the combustion chamber, whereby said gases will be prevented from entering the muffle, 45 for the purpose described.

3. In a muffle furnace, the combination with a combustion chamber and a refractories muffle adapted to be heated by the combustion gases in said chamber, of means for maintaining pressure in the combustion chamber, and means for maintaining within the muffle pressure sufficient to prevent admission thereto of gases from the combustion chamber.

55 4. In a muffle furnace, the combination with a combustion chamber and a refractories muffle adapted to be heated by the combustion gases in said chamber, of means for maintaining pressure in the combustion chamber, 60 and means for supplying air to the muffle and maintaining it under sufficient pressure to prevent the admission thereto of gases from the combustion chamber.

5. In a muffle furnace, the combination 65 with a combustion chamber and a refrac-

tories muffle adapted to be heated by the combustion gases in said chamber, of means for maintaining pressure on the gases in the combustion chamber, and means for supplying air to the muffle under a pressure sufficient 70 to prevent gases from the combustion chamber passing to the interior of the muffle.

6. In a muffle furnace, the combination of a refractories muffle, means for exteriorly heating the muffle by combustion of gas under pressure, and means communicating with the interior of the muffle and adapted to maintain therein a pressure sufficient to prevent the admission thereto of any of the heating gases.

7. In a muffle furnace, the combination of a refractories muffle, a combustion chamber for heating the muffle, a conduit communicating with the interior of the muffle and exposed outside thereof to the heat of products of combustion passing from said chamber, and a blower connected with said conduit, for the purpose described.

8. In a muffle furnace, the combination of a combustion chamber, a muffle within said chamber, means for supplying air under pressure to the interior of the muffle to prevent combustion products from entering the muffle, and means for preheating the air supplied to the interior of the muffle.

9. In a furnace of the type referred to, the combination of a furnace, a muffle within the combustion chamber of the furnace, a conduit exposed to the heat generated in the combustion chamber and provided with a plurality of branches opening into the muffle, and means for forcing air through said conduit under a pressure as great as that produced in the combustion chamber, for the purpose described.

10. In a furnace of the type referred to, the combination of a combustion chamber, a muffle within said combustion chamber, a plurality of burners for heating the muffle, a stack for conducting waste products of combustion from the combustion chamber, a conduit extending longitudinally of the muffle and having a section exposed to the heat of products of combustion passing through the stack, said conduit opening into the muffle, 115 and means for forcing air through said conduit under a pressure as great as that produced in the combustion chamber.

11. In an enameling furnace of the type referred to, the combination of a furnace, a refractories muffle within the combustion chamber of the furnace, a recuperator exposed to the heat of waste products of combustion from the combustion chamber, a conduit connecting the recuperator within the interior 125 of the muffle, and means for forcing air through the recuperator and said conduit under a pressure as great as that produced in the combustion chamber.

12. In an enameling furnace of the type 130

referred to, the combination of a furnace having a combustion chamber opposite side walls of which are each provided with a plurality of openings for burners, a refractories muffle within said combustion chamber, a burner within each of the said burner openings in the walls of the furnace, means for supplying fuel to the burners, and means for supplying air to the interior of the muffle under a pressure as great as that produced in the combustion chamber by the products of combustion of the burners.

In testimony whereof I have hereunto set my hand.
